Fig. 1.

Fig. 2.

*Fig. 4.**Fig. 3.**Fig. 5.*

FIG. 1 is a front elevational view of a clock housing showing my new design, the rear being substantially plain and unornamented;

FIG. 2 is a bottom plan view thereof, the top plan being substantially similar thereto;

FIG. 3 is a right side elevational view thereof, the left side being a mirror image thereto;

FIG. 4 is a sectional schematic view as taken from lines 4-4 of FIG. 1, the internal structural details having been omitted as non-ornamental;

FIG. 5 is a partial sectional schematic view as taken from lines 5-5 of FIG. 1, the internal structural details having been omitted as non-ornamental.

I claim:

The ornamental design for a clock housing, as shown and described.
